UNITED STATES PATENT OFFICE.

THOMAS McMONAGLE, OF BATH, MAINE.

SHAVING-BRUSH.

1,344,050.

Specification of Letters Patent. Patented June 22, 1920.

Application filed July 2, 1919. Serial No. 308,200.

To all whom it may concern:

Be it known that I, THOMAS McMONAGLE, a citizen of the United States, residing at Bath, in the county of Sagadahoc and State 5 of Maine, have invented a new and useful Shaving-Brush, of which the following is a specification.

This invention relates to improvements in shaving brushes, the object of the invention 10 being to provide an improved brush of this character having means for supplying water to the lather end of the brush.

A further object of the invention is to provide a brush of the character set forth and 15 having means for heating the water before it is supplied to the lather.

With the foregoing and other objects in view, which will appear as the description proceeds, the invention consists in the novel 20 features of construction and combination of parts which will be more fully described hereinafter and particularly pointed out in the claims.

In the drawings accompanying and forming part of this specification,

Figure 1 is a side elevation of my improved brush; and

Fig. 2 is a longitudinal section thereof, taken on the line 2—2 of Fig. 1.

30 The same characters of reference designate the same parts in the different figures of the drawings.

Referring to the drawings, the brush comprises a flexible cylindrical member 2 provided with an end-closing member 3 in which the usual tuft of bristles 4 is secured in any suitable manner. The opposite end of the member 2 is closed by a flexible washer 5 of any suitable material, preferably 35 leather. A small tube 6 extends lengthwise of the member 2 centrally thereof and communicates with the opening in the flexible washer 5, such tube being preferably tapered toward its opposite end and extending 40 through the end member 3 of the cylinder 2 into communication with a tube 7, preferably of soft rubber, which is closed at one end and provided with a plurality of small openings 8.

50 Threaded on the upper end of the member 2 is a cylindrical water receptacle 9, one end of which is closed by a bottom 10, from

the center of which extends a tube 11 provided with a plurality of small openings 12. The open end of the tube 11 is adapted to 55 pass through the washer 5 into communication with the inner end of the tube 6.

A third cylindrical member 13 is adapted to have a tight fit at one end thereof on the closed end of the member 2, its opposite end 60 being turned over to provide a small inwardly extending flange 14 adapted to retain a wad of inflammable material 15, such as felt soaked in alcohol. The cap member 13 is provided with a plurality of air holes 65 16 around its circumference.

When it is desired to use the brush, the cylindrical receptacle 9 is removed from the member 2 and filled with water and replaced. The inflammable material carried by the cap 70 13 is then ignited, and when the water in the receptacle is sufficiently heated the brush is ready for use. A slight pressure of the thumb and forefinger on the member 2 will flex the washer 5 so that the water in the receptacle 9 will flow through the openings 12 75 and down the tube 6, to the bristles.

While I have described in detail the structure herein illustrated, it is to be understood that I do not thereby limit my invention to 80 the precise features of construction shown, as I am aware that many mechanical changes and modifications may be made therein without departing from the spirit and scope of the invention as set forth in the claims here- 85 to appended.

Having thus described my invention, what I claim is:

1. In a shaving brush, a flexible cylindrical member, a brush carried by one extremity thereof, a water receptacle supported at the other end of the flexible resilient cylindrical member, means for providing communication between the water receptacle and brush, a flexible washer closing the last 90 named end of the cylindrical member, whereby movement of the side walls of the flexible cylindrical member causes a movement of the washer to force fluid to flow to the brush. 95

2. In a shaving brush, a flexible cylindrical member, a brush supported on one end thereof, a water receptacle removably secured to the other end of the flexible resilient 100

cylindrical member, an apertured tube extending from the water receptacle, means for providing communication between the apertured tube and the brush, means actuated by the walls of the cylindrical member for causing fluid to flow through the apertures and to the brush.

In testimony that I claim the foregoing as my own, I have hereto affixed my signature in the presence of two witnesses.

THOMAS McMONAGLE.
